Primary Examiner — Cynthia Ramirez(74) *Attorney, Agent, or Firm* — Kevin Schraven; Anooj Patel; Hankin Patent Law APC(57) **CLAIM**

The ornamental design for an arm rest, as shown and described.

DESCRIPTION

FIG. 1 is a top perspective view of an arm rest, showing my new design.

FIG. 2 is a bottom perspective view thereof.

FIG. 3 is a front elevational view thereof.

FIG. 4 is a rear elevational view thereof.

FIG. 5 is left-side elevational view thereof.

FIG. 6 is a right-side elevational view thereof.

FIG. 7 is a top plan view thereof; and,

FIG. 8 is a bottom plan view thereof.

The broken lines in the figures show portions of the arm rest which form no part of the claimed drawings.

1 Claim, 8 Drawing Sheets(56)
